UNITED STATES PATENT OFFICE.

CHRISTIAN L. SCHNEIDER, OF DAVENPORT, IOWA.

WINDOW-SASH WEIGHT.

1,426,224.

Specification of Letters Patent. Patented Aug. 15, 1922.

Application filed January 10, 1921. Serial No. 436,193.

To all whom it may concern:

Be it known that I, CHRISTIAN L. SCHNEIDER, a citizen of the United States, residing at Davenport, in the county of Scott and State of Iowa, have invented new and useful Improvements in Window-Sash Weights, of which the following is a specification.

This invention relates to window-sash weights and an object of the invention is to provide a window-sash weight which is substantially rectangular in shape in cross section and constructed so that only two weights need be used in a window structure comprising upper and lower sliding panels.

Another object of the invention is to provide a window-sash weight, the weight of which may be varied as of the window sashes required the said weight being provided with recess openings at the inner upper end of the weight adapted to receive removable lugs.

A further object of the invention is to provide a hook portion on the further end of the weight to which auxiliary weight may be detachably connected when required.

Other objects of the invention will appear in the following detailed description and accompanying drawings wherein:

Fig. 1 is a side elevation, partly in section of the improved window-sash weight.

Fig. 2 is an edge elevation, partly in section of the improved window-sash weight.

Fig. 3 is a cross section on the line 3—3 of Fig. 1.

Referring more particularly to the drawing, the improved sash weight is preferably cast of suitable material, the body 1 thereof is provided with a pair of arms 2 and 3 upon

its upper end, which arms carry a suitable pin 4 upon which a pulley 5 is rotatably mounted, the said pulley, preferably, having concave perimeter for receiving the sash cord and preventing the latter from slipping off the edge of the pulley and binding. The body 1 is provided with a longitudinally extending central recess 6 rectangular in cross section, which opens out in the upper end of the body as shown at 7, the arms 2 and 3 being slightly reduced in thickness for short

distances above the open end 7 to permit the passing of weights or lugs 8 therethrough for depositing in the recess 6 to increase the weight of the body one when necessary. Often it is necessary to increase the weight of the sash-weight over that permitted by use of

the slugs 8 and to allow this increasing of weight a hook 9 is formed upon the lower end of the body 1, the recess in said hook opening out upwardly in a pocket 10, preferably at the longitudinal center of the body 1 as clearly shown in Fig. 2 of the drawing. Two of these hook structures 9 are provided being formed upon the extension 11 of the body 1 and spaced as clearly shown in Fig. 65 2 of the drawings to permit the insertion therebetween of the upstanding lug 12 formed on the auxiliary weight 13. The pin 14 extends transversely through the lug 12 and is provided for seating in the recess in 70 the hooks 9, as shown in Fig. 1 of the drawing to suspend the auxiliary weight 13 from the body 1 of the sash-weight. The inner walls of the pockets 10 are concavely curved so as to form curved guide surfaces for guiding the pin 14 into the pockets or openings of the hooks 9 and the bills 15 of the hooks 9 project upwardly a sufficient distance from the lower ends of the hooks, to prevent accidental removal of the ends of the pin 14 80 from the hooks. To disconnect the auxiliary weight 13 from the body 1 it is necessary to move the auxiliary weight upwardly in a direct vertical line until the pin 14 is passed above the upper ends of the bills 15 after 85 which the weight 13 is moved laterally out of the pockets 10.

It is, of course, to be understood that the invention may be constructed in various other manners and the parts associated in 90 other relations and, therefore, I do not desire to be limited in any manner except as set forth in the claim hereunto appended.

Having thus described my invention what I claim is:

95 A window sash weight comprising a rectangular body having a hook arranged at its bottom end and parallel arms extending from its other end and further having a longitudinally centrally arranged recess 100 that opens out at the base of said arms, and a pulley mounted in the upper ends of the arms so as to be spaced from the open end of said recess, and weights adapted to be passed under the pulleys and deposited in the open 105 end of the recess.

In testimony whereof I affix my signature.

CHRISTIAN L. SCHNEIDER.
